DRY SHAVER

Reinhard Willem Jacob Veersema, Eindhoven, Netherlands, assignor to North American Philips Co., Inc.

Filed Dec. 10, 1959, Ser. No. 58,624

Claims priority, application Switzerland June 30, 1959

Term of patent 14 years

(Cl. D22—3)

FIG.1

FIG.2

FIG.3

FIG.4

FIG.5

FIG. 1 is a perspective view of a dry shaver showing my new design;

FIG. 2 is a side elevation view thereof;

FIG. 3 is another elevational view showing the side opposite to that of FIG. 2;

FIG. 4 is a bottom perspective view; and

FIG. 5 is a top plan view thereof.

I claim:

The ornamental design for a dry shaver, as shown.
